BAIL PULL OR THE LIKE

George R. Sonnenleiter, Rockford, Ill., assignor to Keystone Consolidated Industries, Inc., a corporation of Delaware

Filed May 24, 1968, Ser. No. 12,065

Term of patent 14 years

Int. Cl. D8—03

U.S. Cl. D8—159

FIG. 1.

FIG. 2.

FIG. 3.

FIG. 4.

FIG. 5.

FIG. 2 is a side elevational view thereof;

FIG. 3 is a top plan view thereof;

FIG. 4 is a rear elevational view thereof; and

FIG. 5 is a bottom plan view thereof.

I claim:

The ornamental design for a bail pull or the like, substantially as shown.
